UNITED STATES PATENT OFFICE

163,695

HAND MICROPHONE

Lawrence M. Heineman, Los Angeles, Calif., assignor to Permoflux Corporation, Chicago, Ill., a corporation of Illinois

Application January 26, 1951, Serial No. 13,990

Term of patent 14 years

(Cl. D26—14)

To all whom it may concern:

Be it known that I, Lawrence M. Heineman, a citizen of the United States, residing at Los Angeles, in the county of Los Angeles and State of California, have invented a new, original, and ornamental Design for a Hand Microphone, of which the following is a specification, reference being made to the accompanying drawing, forming a part hereof.

In the drawings:

Fig. 1 is a front elevational view of a hand microphone, showing my new design;

Fig. 2 is a side elevational view thereof;

Fig. 3 is a rear elevational view thereof;

Fig. 4 is a top plan view; and

Fig. 5 is a bottom plan view.

I claim:

The ornamental design for a hand microphone, substantially as shown.

LAWRENCE M. HEINEMAN.
